[57] **CLAIM**

The ornamental design for a eye surgery fixation ring
instrument, as shown and described.

DESCRIPTION

FIG. 1 is a front elevation view of the ring instrument;

FIG. 2 is a back elevation view of the ring instrument seen
in FIG. 1;

FIG. 3 is a left elevation view of the ring instrument seen in
FIG. 1;

FIG. 4 is a top, handle, end view of the ring instrument seen
in FIG. 1; and,

FIG. 5 is a bottom, ring, end view of the ring instrument seen
in FIG. 1.

The right elevation of the ring instrument is a mirror image
of the left elevation view and is otherwise identical thereto.
